[57] CLAIM

The ornamental design for a rowing oar articulator, as shown and described.

DESCRIPTION

FIG. 1 is a top elevational view of the rowing oar articulator showing my new design;

FIG. 2 is a front elevational view taken along lines 2—2 on FIG. 1;

FIG. 3 is a rear elevational view thereof;

FIG. 4 is a bottom elevational view thereof;

FIG. 5 is a right side elevational view taken along lines 5—5 on FIG. 2; and

FIG. 6 is an elevational view of the opposite end taken along lines 6—6 on FIG. 3.

The broken line disclosure is for illustrative purposes only.

FIG. 1.

FIG. 2.

FIG. 3.

FIG. 4.

FIG. 5.

FIG. 6.
